Patented June 15, 1926.

UNITED STATES PATENT OFFICE.

HERMANN ARNDT, OF BERLIN, GERMANY, ASSIGNOR TO SIEMENS & HALSKE AKTIENGESELLSCHAFT, OF SIEMENSSTADT, NEAR BERLIN, GERMANY, A CORPORATION OF GERMANY.

ELECTRIC SIGNALING SYSTEM.

Application filed August 24, 1925, Serial No. 52,032, and in Germany March 28, 1924.

My invention relates to electric signaling systems and particularly to improvements in the known signaling systems as used for railroad purposes in which the signals are given by appropriately colored sources of light so that if a certain track is occupied a red signal appears and if the track is free a green signal.

The object of my invention is to provide means which ensure the highest possible working safety. In order to attain this end in view it is necessary to avoid that in such systems the lighting up of the red lamp be made dependent upon the closing 15 of a contact.

In practicing my invention the above object is attained by short-circuiting the red lamps while the green lamps are lighted up. When the green lamps are extinguished 20 the short-circuiting circuit of the red lamps is opened and the red lamps are lighted up. The lighting up of the red lamps is thus not dependent upon the closing of a contact member.

The operation of the contact member provided for the opening of the short-circuiting circuit may either be mechanically coupled with the contact member which interrupts the circuit for the green lamps or it may by 30 electrical means, such as a relay, be made dependent upon the conditions of the circuit for the green lamps.

In the accompanying drawings attached to my specification and forming part thereof of an embodiment of my invention is illustrated by way of example, Fig. 1 diagrammatically illustrating the general arrangement of the circuits, and Fig. 2 showing a modification of the common switch control, 40 employed in Fig. 1. It has been assumed hereby that the lamps are to be fed by alternating current.

Referring to these drawings 1 is the green go ahead lamp which receives current from the transformer 2 through the line 3 and ground when the contact member 4 is closed. 45 5 is the red stop lamp in parallel relation to which is arranged the short-circuiting circuit 6 with the contact member 7. When 50 the contact member 7 is open this lamp 5 receives current from the transformer 2 across line 9 and ground. If, on the other hand, the contact member 7 is closed, as illustrated in the drawing, the current from

the transformer flows across the shunt 6 so that the lamp 5 is extinguished. The two contact members 4 and 7 may be arranged upon a common contact lever so that when closing the circuit for the green go ahead lamp 1 the red stop lamp 5 is simultaneously short-circuited. In Fig. 1 I have illustrated the mechanical coaction of both contact levers in conventional manner by the hand lever and link interconnection 11, 12, 12, by which both contacts may be simultaneously closed and opened. The opening and closing the contact member 7 may also be made inductively dependent upon the go ahead circuit so that, for instance, when the line 3 is traversed by a current the contact member 7 is closed by a relay in the line 3. This feature is illustrated in Fig. 2 in which 13 signifies the relay located in line 3. When this line is closed to actuate signal lamp 1, relay 13 is energized and by attracting its armature operates link system 14 which in turn closes switch member 7 and thus establishes a short circuit around danger lamp 5. Spring 15 normally tends to keep switch 7 open. The closing of the stop circuit thus depends in this case upon the opening of a contact member so that a considerably greater safety is ensured than if the circuit for the red lamp were conducted through a closed contact member. In order to avoid the source of current 8 being short-circuited when the lamp 5 is short-circuited across the line 6 and the contact member 7, a damping resistor 10 is arranged between the red lamp 5 and the source of current 8 which resistor prevents a detrimental reaction upon the transformer.

If the closing of the contact members of the switch 7 and the bridging over or shunting of the red lamp 5 is not brought about while the green lamp is in circuit both lamps 1 and 5 light up together and thus automatically announce the disturbance in the system. The system is equally well applicable for direct as well as for alternating current. The resistance of the resistor 10 may thus be a purely ohmic resistance or also an inductive or capacitive one. In case of a supply of alternating current the resistor 10 may be saved by employing as source of current a transformer with a large amount of leakage so that when short-circuiting the secondary detrimental reactions

upon the transformer cannot be developed.

Instead of the single signal lamp a plurality of lamps may be connected in parallel relation in known manner.

5 Various modifications and changes may be made without departing from the spirit and scope of the invention, I desire therefore that only such limitations shall be placed thereon as are imposed by the prior art.

10 I claim as my invention:—

In a signal system of the character described, the combination of a current source, a blocking signal lamp connected to said source and a clear track signal lamp connected with said source independently of the

blocking lamp, a short circuit connection in shunt to said blocking lamp for completely extinguishing said lamp, said shunt containing a contact switch for controlling it, 20 a contact switch in said clear track lamp circuit for interrupting its connection with said source, means controlled by the operation of said clear track switch for simultaneously closing said shunt switch with 25 said clear track switch, and means in said blocking lamp circuit for preventing a short circuit of said source when said lamp is extinguished.

15 In testimony whereof I affix my signature.

HERMANN ARNDT.
